UNITED STATES PATENT OFFICE.

WILLIAM P. UHLINGER, OF PHILADELPHIA, PENNSYLVANIA.

LOOM-SHUTTLE.

SPECIFICATION forming part of Letters Patent No. 288,602, dated November 13, 1883.

Application filed May 12, 1883. (No model.)

To all whom it may concern:

Be it known that I, WILLIAM P. UHLINGER, a citizen of the United States, residing at Philadelphia, in the county of Philadelphia and State of Pennsylvania, have invented certain new and useful Improvements in Loom-Shuttles; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention, and is a vertical section of my shuttle. Fig. 2 is a vertical cross-section. Fig. 3 is a perspective view of the spindle. Fig. 4 is a perspective view of the torsion spring.

20 This invention has relation to the shuttles of narrow-ware looms; and it consists in the combination, with a headed spindle, of a perforated torsion-spring, through which the spindle passes, and the shuttle-body formed with a recess in the wall thereof, into which the head of the spindle is pressed by said spring, substantially as specified.

25 In the accompanying drawings, the letter *a* designates the body of the shuttle, in which is made the opening *b* for the spindle carrying the quill. In the inside wall, *c*, at one end of the body *a*, is made a recess, *d*, and opposite this recess, in the opposite inside wall, *e*, of the body, is made a channel-bearing, *g*, the end of which is open at the side of the shuttle, as indicated at *h*.

k represents the spindle, having a rounded head, *l*, which is designed to be seated in the recess *d*, the other end of the spindle being 40 adapted to pass into the bearing *g* when the head *l* is seated in said recess.

s designates a flat or torsion spring, which is secured to the body of the shuttle. It is formed with a bend or extension, *t*, having a 45 perforation or bearing, *m*, through which the spindle is passed, so that when the extension springs against the shuttle-wall the head *l* will engage the recess *d*, and the other end, *v*, of the spindle will be thrown into position in 50 the bearing *g*.

In order to place the quill on the spindle, the latter is turned outward sufficiently to receive it, and will then return to its place, the torsion-spring acting automatically to press 55 the head of the spindle squarely into the recess *d*, and causing the toe *v* of the spindle to return to position in its bearing *g*.

Having described this invention, what I claim, and desire to secure by Letters Patent, 60 is—

The combination, with a headed spindle, of a perforated torsion-spring through which the spindle passes, and the shuttle-body formed with a recess in the wall thereof, into which 65 the head of the spindle is pressed by said spring, substantially as specified.

In testimony whereof I affix my signature in presence of two witnesses.

WILLIAM P. UHLINGER.
